Primary Examiner — Cathron Brooks*Assistant Examiner* — Karen E Kearney(74) *Attorney, Agent, or Firm* — Banner & Witcoff, Ltd.(57) **CLAIM**

The ornamental design for a cartridge drive, as shown and described.

DESCRIPTION

FIG. 1 is a perspective view of a cartridge drive showing my new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The broken lines immediately adjacent the shaded areas represent the bounds of the claimed design and form no part of the claimed design.
